FLUIDIC LOGIC TRAINER COMPUTER

Vincent Randazzo, Brooklyn, N.Y.
(680A Front St., Hempstead, N.Y. 11550)

Filed Aug. 22, 1969, Ser. No. 18,808

Term of patent 14 years

Int. Cl. D14—02

U.S. Cl. D26—5

FIG. 1

FIG. 2

FIG. 3

FIG. 4

FIG. 1 is a front elevation view of a fluidic logic trainer computer;

FIG. 2 is a top plan view of the fluidic logic trainer computer of FIG. 1;

FIG. 3 is a side elevation view of the fluidic logic trainer computer of FIG. 1; and

FIG. 4 is a rear elevation view of the fluidic logic trainer computer of FIG. 1.

The hidden side is the same as the illustrated side.

The broken lines are shown for illustrative purposes only and form no part of the claimed design.

I claim:

The ornamental design for a fluidic logic trainer computer, substantially as shown and described.
